Primary Examiner — Thomas Johannes*Assistant Examiner* — Catherine Posthauer(74) *Attorney, Agent, or Firm* — Harris, Shelton, Hanover and Walsh; Susan B. Fentress(57) **CLAIM**

The ornamental design for an attachable handle, as shown and described.

DESCRIPTION

FIG. 1 is an isometric view of an attachable handle showing my new design in an assembled configuration enlarged for clarity of construction;

FIG. 2 is a front view thereof, the rear view being identical;

FIG. 3 is a right side elevation view thereof;

FIG. 4 is a left side elevation view thereof;

FIG. 5 is a top view thereof;

FIG. 6 is a bottom view thereof;

FIG. 7 is an isometric view thereof, in an unfolded configuration, shown at a reduced scale for clarity of dimension;

FIG. 8 is a front view thereof, the rear view being identical;

FIG. 9 is a right side elevation view thereof;

FIG. 10 is a top view thereof.

FIGS. 1-6 enlarged for clarity of construction.

1 Claim, 6 Drawing Sheets(56)
